UNITED STATES PATENT OFFICE.

WILLIAM H. WHITE AND HIRAM F. RUDDELL, OF ATLANTA, GEORGIA.

CAR-COUPING.

SPECIFICATION forming part of Letters Patent No. 287,749, dated October 30, 1883.

Application filed July 28, 1882. (No model.)

To all whom it may concern:

Be it known that we, WILLIAM HENRY WHITE and HIRAM F. RUDDELL, both citizens of the United States, residing at Atlanta, in 5 the county of Fulton and State of Georgia, have invented a new and useful Car-Coupling, of which the following is a specification.

Our invention is a car-coupling constructed as fully described hereinafter, whereby the automatic and positive coupling together of cars is effected with celerity and dispatch.

In the drawings, Figure 1 represents a side elevation of a car-coupling having our improvement embodied therein; Fig. 2, a front elevation of Fig. 1; Fig. 3, a longitudinal section on the line 1 2, Fig. 2. Fig. 4 is another side view.

In a box or case, T, secured to the bottom of the car is bolted the draw-head R, having a 20 buffer-spring interposed between its rear portion and the end of the box or case, so as to admit of a limited longitudinal play of the draw-head within the said case T. The usual protruding portion of the draw-head is recessed for the reception of the coupling-link Q, and has also a vertical link-perforation, of 25 peculiar contour, in which plays the coupling-link A, of the shape shown in dotted lines, Fig. 1, and full lines in Fig. 2—namely, an 30 elongated wedge shape, with the apex a of the wedge resting in a corresponding recess in the link-perforation when the link is in its normal position in the draw-head. The link has also an extension or arm, b, which extends 35 rearward in the link-recess, and provided with an elongated slot, c², through which passes transversely a pin, N, secured to the sides of the draw-head, and a lip or shoulder, e, which bears (when the coupling-link rests snugly 40 within the pin-perforation) on a pin, o, extending across the coupling-recess parallel with the pin e.

The front portion of the draw-head is provided on each side with curved vertical slots 45 f, in which plays one of the ends of a bar, G, transversely arranged in the coupling-recess, and having its ends projecting through the slots f from the exterior of each side of the draw-head, where they are connected to horizontal levers K, pivoted centrally to the side 50 of the draw-head, and the other sides of which are attached to vertical levers J, each con-

nected to short arms F, keyed on a shaft, C, journaled in brackets g, secured to face of the car.

The partial revolutions of the shaft C are effected by two hand crank-levers, E, each attached rigidly to one end of the said shaft C, and preferably located a short distance from the side of the car, so as to avoid any necessity for 55 dangerous proximity during the coupling operation. A sleeve or collar, B, centrally located on the shaft C, turns loosely thereon, and is cut away at h h, so as to have its end portions bear on the arm P of the said shaft C, 60 and is, moreover, provided with a centrally-projecting arm, B', connected to the coupling-link A by means of a chain, i.

The operation is as follows: Either of the 70 levers being swung in the direction of the arrow, Fig. 3, the shaft C is revolved, so as to elevate its arms F, which indirectly raise the arm B' by turning the sleeve B, the coupling-pin A, by reason of the chain-connection i, being elevated in consequence. When the coupling-pin is elevated, its shoulder e slides on the pin o, while the rear portion of its extension b moves toward the bottom of the draw-head until the pin N in the slot c prevents further movement. The pin can now remain in this 80 position, if it is desired, until the coupling operation is to occur, when the thrust or shock of the entrance of the coupling-link will be sufficient to enable the pin to resume its original position by gravity. When the arms F 85 or the shaft C are elevated by the revolution of said shaft in raising the coupling-pin, the rods J are raised therewith, moving the levers K on their pivots, so as to depress the forward ends of said levers, and likewise the 90 transverse bar G, which is thus prevented from presenting any obstruction to the entrance or withdrawal of the link, as circumstances may require.

It will be apparent that by swinging either 95 of the levers in a reverse direction to that previously described the cross-bar G can be elevated in a corresponding degree, this movement and that previously described enabling the said bar G to be so adjusted as to guide 100 the entrance of the link-coupling Q at any angle.

It will also be obvious that by forming the coupling-pin A with the central enlargement,

a, the pin is materially strengthened in the line of the draft, and will better resist the strain in that direction than pins usually employed.

Having fully described our invention, what we claim as new, and desire to secure by Letters Patent, is—

1. The combination, in a car-coupling, of a shaft, C, turning in brackets on the car above the draw-head, having arms F, and a loose collar, B, turning on the shaft C, and having arm B', and cut away to bear on the arms F, and connected to the coupling-link by a chain, *i*, and devices for effecting the rotation of the shaft C, substantially as set forth.

15 2. The combination, in a car-coupling, of the shaft C, turning in brackets on the car above the draw-head, having arms F, and a

loose collar, B, turning thereon, and having an arm, B', connected to the wedge-shaped pin A, substantially as set forth.

3. The combination, in a draw-head, of the shaft C, turning in brackets on the car above the draw-head, and connected and arranged with devices when revolved to elevate the coupling-link, of rods J, connected to the centrally-pivoted levers K, which are connected with the ends of the bar G, playing in the slots *f* of the draw-head, substantially as and for the purpose set forth.

WILLIAM HENRY WHITE.
HIRAM F. RUDDELL.
